UNITED STATES PATENT OFFICE.

JOSEPH NOWAKOWSKI, OF DETROIT, MICHIGAN.

ELASTIC MAILED SLEEVE FOR TIRES.

1,359,910.

Specification of Letters Patent. Patented Nov. 23, 1920.

Application filed May 27, 1918. Serial No. 286,762.

To all whom it may concern:

Be it known that I, JOSEPH NOWAKOWSKI, (Polish, at present a subject of Germany, but have declared my intention to become a citizen of the United States,) residing at Detroit, county of Wayne, State of Michigan, have invented a certain new and useful improvement in Elastic Mailed Sleeves for Tires, and declare the following to be a full, clear, and exact description of the same, such as will enable others skilled in the art to which it pertains to make and use the same, reference being had to the accompanying drawings, which form a part of this specification.

This invention relates to an elastic mailed sleeve for tires, shown in the accompanying drawings and more particularly described in the following specification and claims.

20 One of the objects of this invention is to provide an inner elastic protective sleeve or shoe adapted to be lodged within the outer casing of a pneumatic tire to inclose the inner tube to protect it from puncture. The 25 shoe is constructed of elastic webbing and shaped to conform to the inner tube and is provided with relatively small overlapping concave metallic scales or plates, secured at one of their edges to the webbing, the 30 free edges of each plate overlapping like adjacent plates, which together form a protective metallic flexible covering for the inner tube that the latter may be insured against puncture.

35 With the foregoing and other objects in view which will appear as this description proceeds, the invention resides in the combination and arrangement of parts and in the details of construction hereinafter described and claimed, it being understood that changes may be made in the precise embodiment of the invention herein disclosed without departing from the spirit of the same.

45 In the accompanying drawings:—

Figure 1 is a perspective view of an elastic inner shoe formed of webbing inclosing strands of rubber, a portion being broken away to indicate its construction.

50 Fig. 2 is a similar perspective view showing the application of a few of the relatively small overlapping metallic plates or scales attached to the elastic webbing.

55 Fig. 3 is a perspective view of the protective shoe as it would appear when completed.

Fig. 4 is a cross-sectional view through an outer casing, the protective shoe, and the inner tube of a pneumatic tire.

Fig. 5 is a similar cross-sectional view showing a modification of the protective sleeve in which the "scales" are carried down on the sides of the tube to a greater extent than is shown in the preceding view.

Fig. 6 is an elevation of one of the concave scales, or plates.

Referring now to the letters of reference placed upon the drawings,—

A, denotes an annular ring or sleeve, formed of a woven strip, or webbing, in the wall of which is embedded strands of rubber.

B. The ring or sleeve A, is divided along its inner periphery to receive the inner tube C.

D, are relatively small metallic plates or scales arranged lengthwise in abutting relation to each other, in rows arranged transversely of the annular sleeve A, and secured along one of their edges to said sleeve, the free edges of the scales being arranged to overlap the edges of like adjacent scales secured to the sleeve. The rows are of different lengths and arranged in alternating relation so that their opposite ends will be equidistant from the opening along the inner periphery of the sleeve A.

The scales may be secured to the shoe along the line of the tread of the tire, as shown in Fig. 4, and they may be carried down the sides of the sleeve as indicated in Fig. 5, if desired. The scales may be either riveted, sewed or otherwise secured to the sleeve.

Having thus described my invention what I claim is:

1. In a device of the character described, a circumferential continuous annular sleeve of substantially uniform thickness throughout formed of elastic woven webbing and open at its inner periphery to receive an inner tube and completely incasing the same, a plurality of substantially rectangular relatively small concave metallic plates arranged lengthwise in rows transversely of the annular sleeve, said rows being of alternate lengths and having their ends equidistant of the said opening of the inner periphery of the elastic sleeve and the plates of each row having their ends in abutting relation and the said plates overlapping the plates of the adjacent rows, and means located adjacent one edge of the plates and located within the contour of the same for securing the

said plates to the sleeve, said attaching means being in transverse alinement and the opposite edges of the plates being free and in the said overlapped relation with the plates of the adjacent rows.

2. An armor for the inner tubes of pneumatic tires, comprising an annular sleeve of elastic webbing completely inclosing the inner tube, a plurality of transverse rows of elongated plates applied to the sleeve, each plate of each row extending lengthwise in a direction transversely of the sleeve and provided with a pair of relatively spaced openings near one of its side edges, and elements

located wholly within the contour of the 15 plates and passing through said openings to secure the plates to the sleeve, the plates of each row having their adjacent end edges arranged in abutting relation and the free sides of the plates of one row overlapping 20 the attached sides of the plates of the adjacent row.

In testimony whereof I sign this specification in the presence of two witnesses.

JOSEPH NOWAKOWSKI.

Witnesses:

S. E. THOMAS,

LEON LEWAMBURKI.
